DESCRIPTION

U.S. PATENT DOCUMENTS

FIG. 1 is a front perspective view of an exhaust stack showing
inventor's new design;

6,357,522 B2 * 3/2002 Dienhart et al. 165/183
6,378,559 B1 * 4/2002 Humphryson 137/849
6,474,839 B1 11/2002 Hutchison
6,582,108 B1 6/2003 Liang
6,588,923 B1 7/2003 Shih
6,623,134 B1 9/2003 Chang
6,637,537 B2 * 10/2003 Porter et al. 180/309
6,648,022 B2 * 11/2003 Pentz et al. 138/37

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view;

Portions of the exhaust stack shown in broken lines in FIG. 7
are environment and form no part of the claimed design.
